VACUUM CLEANER WITH CORD RING

Clarence G. Frantz, Cleveland Heights, Ohio, assignor to
Frantz Electric Industries Inc., Cleveland, Ohio, a cor-
poration of Florida

Filed Apr. 1, 1963, Ser. No. 269,602

4 Claims. (Cl. 15—323)

This invention relates generally to vacuum cleaners and more particularly to a novel and improved canister type vacuum cleaner having a rim around which the electric cord can be stored and within which the cleaner tools may be stored.

Canister and tank type cleaners are normally provided with a variety of tools, each of which is designed to efficiently perform a particular type of cleaning operation. It is desirable to retain all of these tools with the cleaner so that they are conveniently available for use at all times. It is also desirable to permit the convenient storage of the tools with the cleaner during periods of non-use so that one or more of the tools will not become lost or misplaced.

Still further, it is desirable to arrange the cleaner with a convenient means for easily and neatly storing the electric cord during periods of storage so that the cord will not become tangled or caught with other items also stored in the same location as the cleaner.

In a vacuum cleaner incorporating this invention, a circular ring or rim is mounted on the upper end of the housing which provides a reel for a cord storage and also supplies a tray for the tool storage. Therefore, the tools are conveniently stored with the cleaner so that they will not become mislaid or lost and are always available when the cleaner is in use. These useful functions are achieved by a simple low-cost structure which also serves to enhance the appearance of the cleaner and protect it against damage.

It is an important object of this invention to provide a novel and improved combination cord reel and tool storage structure for vacuum cleaners and the like.

It is another important object of the invention to provide a novel and improved canister type cleaner having a rim portion at the upper end thereof for storing the electric cord of the cleaner and also the various cleaning tools.

It is still another object of the invention to provide a novel and improved vacuum cleaner of the canister type having a decorative rim on the upper end thereof which enhances the appearance of the cleaner and serves the function of providing for storage of the electric cord and cleaning tools.

It is still another object of this invention to provide a novel and improved canister type vacuum cleaner having a flanged rim on the upper surface thereof and a centrally located handle wherein the flanged rim is arranged for storage of the electric cord and the area within the rim around the handle is for the storage of the cleaning tools.

Further objects and advantages will appear from the following description and drawings wherein:

FIGURE 1 is a perspective view of a canister vacuum cleaner incorporating this invention;

FIGURE 2 is a perspective view similar to FIGURE 1 illustrating the cleaner with the electric cord wrapped for storage around the rim and cleaning tools supported on the cleaner; and

FIGURE 3 is a fragmentary section illustrating one preferred structure of the rim and its mounting upon the housing of the vacuum cleaner.

This invention is illustrated as incorporated in a typical canister type vacuum cleaner having a housing 10 supported for rolling along the floor on casters 11. Lo-

2

cated within the housing 10 is the usual electric motor driven fan operable to create a vacuum in the vacuum chamber of the housing 10. Also enclosed within the housing 10 is a dirt separating mechanism which may be a bag type filter.

10 A flexible hose 12 couples to the housing 10 at the one end and is adapted at its other end for mounting a wand or tools. Any one of a variety of tools such as a furniture nozzle 16, a crevice tool 17 or a brush tool 18 may be connected or mounted either directly on the hose 12 or the wand. Each of these tools 16, 17 and 18 is proportioned and constructed to efficiently perform a particular type of cleaning operation. Therefore, it is customary in the use of the vacuum cleaner to frequently change the tools and use that tool best suited for the particular operation being performed. It is, therefore, desirable to retain all of the tools with the cleaner at all times so that each tool will be conveniently available for use.

20 An electric cord 19 extends through a grommet 20 in the housing 10 to the electric motor and is provided with a normal household type plug at its end.

The housing 10 is formed with a generally circular upper end wall or surface 21 joined to a side wall 22 by a conical portion 23 and a radius portion 24. Mounted on the upper end 21 of the housing 10 is a mounting rim 26 formed with a cylindrical portion 27 and an inwardly extending lower end flange 28. The mounting rim 26 is also formed with spaced outwardly extending radial flanges 29 and 31 at opposite ends of the cylindrical portion 27. Screws 32 fasten the flange 28 to the end wall 21 of the housing 10. In the illustrated embodiment, the mounting rim is formed of two pieces 33 and 34 each formed as a stamping. The piece 34 has a cylindrical section 36 spot-welded to the cylindrical portion 27 and provides the flange 31.

30 A ring 37 molded of plastic material such as vinyl plastic or any other suitable material is mounted on the mounting rim 26. The plastic ring 37 is formed with a vertically extending portion 35 and integrally formed spaced outwardly extending flanges 38 and 39 at opposite ends thereof. The inner wall of the ring 37 is recessed at 41 to fit over the cylindrical section 36 of the piece 34 and is formed with radially extending grooves 42 and 43 to receive the flanges 29 and 31, respectively. The upper flange 38 of the ring 37 is formed with a conical upper surface 44 and a conical lower surface 46 which are proportioned to converge as they extend toward 40 a radius 47 joining their ends. The central portion 35 is formed with an increasing radius as it extends downward toward the flange 39 and is blended at both ends by radius portions 48 and 49 to the inner walls of the flanges 38 and 39. A bead 51 is formed at the outer extremity of the flange 39 and is proportioned to engage the conical portion 23 of the housing 10. Preferably the cylindrical portion 27 of the mounting ring 26 has a diameter greater than the upper end of the conical portion 23 to provide a recess between the lower flange 31 of the mounting ring and the conical portion 23. An inwardly extending projection 52 on the ring 37 extends into this recess and provided stiffness for the ring.

45 The material of the ring 37 is sufficiently elastic to permit the ring 37 to be stretched over the mounting ring 26 and snapped into position. Also the ring is molded so that the bead 51 presses tightly against the conical portion 23 of the housing 10 to prevent entry of dirt and the like.

50 FIGURE 2 is a perspective view similar to FIGURE 1 illustrating the cleaner with the electric cord wrapped for storage around the rim and cleaning tools supported on the cleaner; and

55 A U-shaped handle 53 is mounted with one leg thereof on the end 21 of the housing 10 and is located centrally of the mounting ring 26. The opposite leg of the handle

provides a comfortable gripping portion used when the cleaner is carried.

The zone within the mounting ring 26 provides sufficient capacity for the storage of the tools and nozzles not being used at any given time. Therefore, the tools are carried by the cleaner both during the use of the cleaner and during the storage thereof. The cord 19 is wound around the ring 37 between the flanges 38 and 39, as illustrated in FIGURE 2, when the cleaner is not in use so that it is conveniently and easily stored and is not subjected to angling or the like.

A vacuum cleaner incorporating this invention is attractive in appearance and utilitarian in function since it provides a convenient storage for the tools not in use and a convenient cord drum to receive the electric cord when the vacuum cleaner is not in use. The plastic ring 37 serves to protect the cleaner and furniture since the plastic is resistant to chipping, denting and scratching. In addition the plastic ring operates, by its engagement with and mounting on the housing to dampen vibration and reduce noise.

Although a preferred embodiment of this invention is illustrated, it is to be understood that various modifications and rearrangements of parts may be resorted to without departing from the scope of the invention as defined in the following claims.

What is claimed is:

1. A vacuum cleaner comprising a housing, having a generally horizontal upper surface, a metallic rim mounted on said upper surface formed with an upstanding portion and radially extending spaced flanges at each end of said portion, and a ring of molded plastic fitting around said rim and formed with grooves into which said flanges extend, said ring having spaced radially extending flanges and an upwardly extending section therebetween, the inner portion of said ring above the upper one of said flanges of said rim extending into substantial alignment with the inner surface of said upstanding portion whereby the upper edge of said metallic rim is substantially covered by said plastic ring.

2. A canister vacuum cleaner comprising a housing having a circular horizontal upper end joined directly to a conical section, a rim mounted on said upper end having a lower flange extending laterally beyond said upper end, said rim including a vertically extending portion

joined to said lower flange, a flexible molded ring mounted on said rim formed with an upper laterally extending flange and a lower laterally extending flange spaced from said upper flange, the extremity of said lower flange of said ring tightly engaging said conical section, and a handle centrally located within said rim mounted on said upper end.

3. A canister vacuum cleaner comprising a housing having a circular horizontal upper end joined directly to a conical section, a rim mounted on said upper end having a lower flange extending laterally along said upper end, said rim including a vertically extending portion joined to said lower flange, a flexible molded ring mounted on said rim formed with an upper laterally extending flange and a lower laterally extending flange spaced from said upper flange, a bead on the extremity of said lower flange of said ring tightly engaging said conical section, and a handle centrally located within said rim mounted on said upper end.

4. A canister vacuum cleaner comprising a housing having a circular horizontal upper end joined directly to a conical section, a rim mounted on said upper end having a lower flange extending laterally beyond said upper end above and spaced from said conical section, said rim including a vertically extending portion joined to said lower flange, a flexible molded ring having a portion extending between said conical section and said lower flange of said rim, said rim formed with an upper laterally extending flange and a lower laterally extending flange spaced from said upper flange, the extremity of said lower flange of said ring tightly engaging said conical section, and a handle centrally located within said rim mounted on said upper end.
